HENRY C. OSBORN, OF CLEVELAND, OHIO, ASSIGNEE TO THE AMERICAN MULTIGRAPH COMPANY, OF CLEVELAND, OHIO, A CORPORATION OF OHIO.

MECHANISM FOR STORING, ASSEMBLING, AND DISTRIBUTING TYPE.

1,076,906.

Specification of Letters Patent.

Patented Oct. 28, 1913.

Application filed April 23, 1903. Serial No. 428,834.

To all whom it may concern:

Be it known that I, HENRY C. OSBORN, a citizen of the United States, residing at Cleveland, in the county of Cuyahoga and State of Ohio, have invented a certain new and useful Improvement in Mechanism for Storing, Assembling, and Distributing Type, of which the following is a full, clear, and exact description, reference being had to the accompanying drawings.

My prior application No. 384,912, filed July 22, 1907, shows a very efficient mechanism for storing, assembling and distributing type, wherein there is a rotary storage member into which type may be distributed one at a time, or from which it may be assembled one at a time, a suitable finger key being provided for each operation.

The present invention is designed as an addition and improvement on that referred to.

It comprises means whereby a whole line of type, or any portion thereof, may be passed at one time and by one operation into the storage member, or passed from such storage member into the receiving member.

The invention consists of the means I employ to enable the accomplishment of this operation as hereinafter more fully described.

As shown in the drawings, Figure 1 is a front elevation of my mechanism; Fig. 2 is a plan of a portion of the machine; Fig. 3 is a vertical section through the distributing slide and adjacent parts; Fig. 4 is a similar section through the assembling slide and adjacent parts; Fig. 5 is a section through the locking bolt of the distributing slide; Fig. 6 is a plan of a portion of one of the slides; and Fig. 7 is a perspective view of a type adapted to be carried by the embodiment shown, and Fig. 8 shows part of a type holder.

Referring to the parts by reference numerals, 10 represents the base, 11 the top plate and 12 vertical rods connecting these members, such parts constituting the frame of the machine. Journaled in the base and top plate is a shaft 13 which carries at its upper end a hand wheel 14 by which it may be rotated and carries between the base and top plate suitable spiders 17 and 15 which carry at their peripheries vertical rails 16, 55 which rails provide between them type re-

ceiving channels. The type may be of the form shown in Fig. 7, having grooves 21 on their opposite sides, which grooves are adapted to be occupied by the overhanging edges of the rails 16. These type are shown at 20 in Fig. 1, the storage member being shown as nearly empty in this view for convenience.

The type to be distributed are contained in a suitable column type holder (omitted in Figs. 1 to 4) which is suitably held above the top plate 11. This type holder may be a split tube, as shown at 35 in Fig. 8, the edges of the tube adjacent to the split entering the grooves of the type. This tube 70 is adapted to be carried in the partially tubular socket 23 in a block 24, which is normally stationary between guiding walls rising from the top plate but is shiftable radially for a purpose hereinafter explained. 75 Similarly, a split tube for receiving the type being assembled is carried by a partially tubular socket 25 on the front side of a block 26 mounted on the base. These split tubes may be held in their respective sockets by their own elasticity. Beneath the socket 23 is a pair of parallel plates 27 providing a distributing raceway which is a continuation of the channel provided by the split tube in the socket. Similarly the receiving tube has its channel continued by plates 28, which constitute an assemblage raceway.

With a structure as above described, it will be seen that it is only necessary, in distributing, to turn the drum by its hand wheel to bring the proper channel, provided by adjacent rails 16, into position, and transfer the type from the distributing raceway into such channel. Similarly, in assembling, 95 the drum is turned by the hand wheel to bring the proper channel to the front, and suitable transfer mechanism is operated to convey the type from the bottom of the drum into the assembling raceway. These 100 transfer mechanisms will now be described.

Slidably mounted in a radial groove 40 on the under side of the top plate 11 is a sliding plate 41. This plate is of the same thickness as the corresponding dimension 105 of the type and has an opening 42 formed of the proper shape to receive the type. This opening is normally directly below a column of type in the distributing raceway and holder, so that the bottom type nor- 110

- mally occupies the opening. A plate 43 carried by the frame below the opening prevents the type from dropping out of the slide. The slide is normally in its outer- 5 most position and when shoved inward, the single type contained in the opening 42, is carried over the upper end of the type channel located beneath it, and accordingly drops into that channel.
- 10 To assemble the type from the lower end of the drum into the assembling raceway and holder, there is provided an identical slide 51 mounted in a radial groove 50 in the upper face of the base plate 10. This 15 slide has a type carrying opening 52 normally located over the assembling raceway. The lowest type in the drum channel which is at the front, normally rests on the top of slide 51. When the slide is pushed rearwardly, the bottom type in the drum channel drops into the opening 52, and on the return movement of this slide, this type is dropped into the column for assembling.
- Each of the slides 41 and 51 is normally 20 held in its forward position by a spring 44, which is secured at one end to a stationary stop 45 and at the other to a pin 46 secured to the slide. A suitable pin 47 extending through a slot 48 in the slide limits the 25 movement of the slide. A head or knob 49, may be provided at the outer end of the slide, to receive the operator's thumb or finger, whereby the slide may be conveniently pushed rearwardly.
- 30 The periphery of the hand wheel 14 may have indicating characters coöperating with a pointer 61, Fig. 1, to enable approximate positioning of the supply drum; and there may be provided on the supply drum rings 35 64 having V-shaped notches with which a lug 67 on the corresponding slide coöperates, to accurately position the drum whenever a slide is operated.
- The mechanism so far described, with the 40 exception of the means for carrying the typeholders, is that shown and described in my prior application, referred to, enables type to be fed one at a time into the drum or out of the drum. To allow whole lines 45 of type or any portion thereof to be fed at one time either into or out of the drum, the arrangement which constitutes the subject matter in this application is employed. The type holders in this case are not mounted 50 rigidly in the top plate or base of the machine as in my prior application, but, as heretofore stated, in blocks 24 and 26 as the case may be, which are mounted on the front portion of the top plate and base respectively. These blocks have secured to them 55 rods 72 which extend loosely through the associated bosses 70 and 71 of the corresponding frame member and have on their ends adjusting nuts 74. Springs 75 surrounding 60 the rods tend to keep the blocks in their for-

ward position. In this position, the holders are held out of alinement with the drum channels and in alinement with the openings in the slides the same as when the holders are in stationary sockets.

70 There is a possible movement for the block and holder together equal to the movement of the slide. Each block is provided with a bolt 76 normally held in inactive position by a spring 77. Whenever desired, however, this bolt by the simple pressure of the operator's finger on the end thereof may be forced into a hole 78 in the corresponding slide, thereby locking the block to the slide so that when the slide is pushed inward, the block and type holder move with it, bringing the type holder, the opening in the slide, and a channel of the drum all into alinement, so that a whole line or any portion thereof may be shifted as desired.

75 The elasticity of the type holders may hold them in place, but proper position in the blocks is insured by suitable pointed plungers 80 mounted in the blocks and each entering a corresponding opening in the 80 type holder. To keep this plunger in normal engagement and still allow movement of the block, the plunger extends into the associated frame member and is therein surrounded by spring 81. The holder may 85 be shoved into its socket across the pointed nose of this plunger which springs into place when the holder is in final position and retains the holder until it is drawn out by sufficient force.

90 The construction above described enables the drum to be stored quickly. It also provides for the easy correction of errors in assembled lines. The holder with the assembled lines in it may be placed above the 95 drum, the portion of the line below the improper character dropped into an empty channel in the drum, as above described, then the improper character distributed to the proper channel in the drum by the normal operation of the distribution slide and the turning of the drum, then the portion of the line in the storage drum dropped as a whole into the receiving holder, then the proper character assembled in such holder 100 by the normal operation of the assemblage slide and drum, and finally the balance of the line dropped by gravity from the upper holder through a blank channel in the drum into the lower holder, by reason of the various slide openings being all brought into alinement with this channel, as above described.

105 The invention in no manner interferes with the efficient normal operation of distributing or assembling as described in my prior application, but forms a valuable addition thereto.

I claim:—

110 1. The combination of two typeholders be-

- 5 between which type may be transferred, mechanism for limiting the transfer to one type at a time, means for moving one of the type-holders to a position where the limiting mechanism does not restrict the transfer to one type at a time, whereby a whole line may be continuously transferred.
- 10 2. The combination of two typeholders adapted to be out of alinement, means for transferring type from one to the other when out of alinement, and means for bringing them into alinement to allow type to pass from one directly to the other.
- 15 3. The combination of mechanism adapted to hold a plurality of lines of type, two typeholders, and means for feeding lines from one holder to the mechanism and from the mechanism to the other holder, one at a time, or a whole line, or a fraction thereof 20 at a time, as desired.
- 25 4. The combination of a type case having channels down which type may descend by gravity, means for limiting the descent, mechanism for assembling type therefrom by the assistance of gravity, said mechanism being arranged to limit the transfer to a single type at a time or a line of type, and a single key for causing both operations, as desired.
- 30 5. The combination of a type case, mechanism for distributing type thereinto by the assistance of gravity, and mechanism for assembling type therefrom by the assistance of gravity, each of said mechanisms being arranged to transfer a single type at a time or a line of type, as desired.
- 35 6. The combination of a type holding member having a plurality of type holding channels, a type holder, a slide between them adapted to aline with either the said type holder or a channel of the member, and means for locking the type holder to the slide.
- 40 7. The combination of a rotary type holding drum having a plurality of type holding channels, a column type holder, a slide between them adapted to aline with either the column type holder or a channel of the drum, and means for locking the column type 45 holder to the slide.
- 45 8. The combination of a movably mounted type-holder adapted to carry a line of type, a storage member having a plurality of type holders, a transfer slide between the type-holders, said slide having an opening adapted to aline with either, and means for locking the slide and one of the type-holders together.
- 50 9. The combination of a movable block adapted to carry a line of type, a storage drum having a plurality of type holders, a transfer slide between the drum and block, said slide having an opening adapted to aline with either the line of type carried by 55 the block or a channel of the drum, and means for locking the slide and block together.
- 100 10. The combination of two type holders, a transfer slide between them, said slide having an opening adapted to aline with either type holder, means for locking the slide and one of the type holders together, a spring tending to hold such parts in position out of alinement, and a spring tending to release said lock.
- 105 11. The combination of a movable channeled block adapted to carry a line of type, a storage drum having a plurality of type holders, a transfer slide between the drum and block, said slide having an opening 70 adapted to aline with either channel of the block or a channel of the drum, means for locking the slide and block together, a spring tending to hold said block in position out of alinement with a channel of the 75 type drum, and a spring tending to release said lock.
- 110 12. The combination of a storage member and a type-holder adapted to be out of alinement, means for transferring type from one 80 to the other when out of alinement, and means for bringing them into alinement to allow type to pass directly from one to the other.
- 115 13. The combination of a storage member and typeholder, an interposed slide, a movable member carrying the type holder, and means for temporarily locking said member to the slide to enable them to move in unison.
- 120 14. The combination of a storage member and type holder, an interposed slide, a movable member carrying the type holder, means for temporarily locking said member to the slide to enable them to move in unison, and a spring tending to release such lock.
- 125 15. The combination, with a rotary vertical type-holding drum and means for turning it, of mechanism for feeding type 85 into the upper end thereof, and mechanism for limiting the descent of type therein and for discharging out of the lower end thereof at a single operation a whole line of type.
- 130 16. The combination with a rotary vertical type holding drum, hand operated mechanism for discharging into the upper end thereof a whole line of type; and hand operated mechanism for discharging a whole line from the lower end.
- 135 17. In a combined type case and assembling mechanism, a storage member, a finger operated mechanism for feeding type into one end of it, and means whereby said finger operated mechanism may feed one type 120 at a time or a line at a time.
- 140 18. In a combined type case and distributing mechanism, a storage member, a finger operated mechanism for feeding type out of one end of it, and means whereby 130

1. said finger operated mechanism may feed one type at a time or a line at a time.

2. In a combined type case and assembling and distributing mechanism, a storage member, a finger operated mechanism for feeding type into one end of it, a second finger operated mechanism for feeding type out of the other end of it, and means co-operating with said finger operated mechanism to feed a line at a time.

3. The combination, with two type holders normally out of alignment, of an interposed laterally movable slide arranged to receive the end type of a line in one holder and transfer it laterally to the other, and means whereby one of said type holders may be locked to said slide.

4. The combination, with two type holders normally out of alignment, of an interposed laterally movable slide arranged to receive the end type from one holder and transfer it laterally to the other, a spring tending to hold one of said holders in normal position, means whereby one of said type holders may be locked to said slide to move with it against said spring.

5. A machine having two finger operated transfer mechanisms, a vertical rotary drum which may be turned to bring any of a number of channels thereof into co-operation with the respective transfer mechanisms, and means co-operating with said transfer mechanisms, whereby there may be transferred one type at a time or a line at a time.

6. A machine having a rotary type holding drum, line type holders, transfer mechanisms comprising laterally movable slides located respectively adjacent to the two ends of the drum, and means whereby one of said type holders may be locked to one of said slides.

7. The combination, with mechanism adapted to hold a plurality of lines of type and a type holder, of a movable member by which said holder is carried, which member normally holds the holder out of alignment with said mechanism but allows it to be displaced to be brought into alignment therewith, and means for transferring type from the holder to said mechanism when out of alignment.

8. The combination with a storage member and a type holder of a transfer slide, a block which normally holds the type holder in alignment with an opening in the transfer slide, and a finger operated bolt so arranged that by the pressure of the finger the block with the type holder may be bolted to the slide and thereby move with it into alignment with a channel of the storage member.

9. The combination with a split tube type holder, of a block having a socket for receiving it, and a spring pressed plunger

10. entering the socket and adapted to engage the holder.

11. The combination of two type holders adapted to be out of alignment, a slide for transferring type from one to the other when out of alignment, and means for causing one of the holders and slide to move in unison to bring them into alignment with the other holder.

12. A machine having a rotary type-holding drum, transfer mechanism including a laterally movable member located adjacent to one end of the drum and adapted to transfer type thereto, one at a time, and means for allowing the transfer of a whole line of type at a time.

13. The combination of two typeholders and manually operated means for feeding type one at a time, and additional means operated by the same manual means for feeding several at a time, as desired, from one holder to the other.

14. The combination of two type holders, one of which is capable of movement with reference to the other, and manual means for feeding the type from one holder to the other one at a time without such movement or several at a time by employing such movement, as desired.

15. The combination of mechanism adapted to hold a plurality of lines of type, a type holder adapted to occupy two positions, and two independent manually-operated means for feeding at one operation a line of type from the holder in one position to the mechanism, or from the mechanism to the holder in the other position and for feeding at one operation only the foremost type in such line to or from said mechanism.

16. The combination of an upright type case, mechanism for distributing into the upper end thereof at one operation a line of type or only the foremost type in the line, and in the latter case to engage the foremost type to limit the transfer to one type at a time, and mechanism for discharging type from the lower end of the case.

17. The combination of two type holders adapted to be out of alignment, means for bringing them into alignment and allowing the transfer at such time of a whole line of type, and means for transferring at one operation only the foremost type in the line when said holders are out of alignment.

18. The combination of a type holding member having a plurality of type holding channels, a type holder, mechanism adapted to align with either said type holder or one of said channels and transfer a single type from one to the other, and means for causing said type holder to move consequent upon the movement of said mechanism.

19. The combination of a type holding member having a plurality of type holding

channels, a type holder, a slide between them having an opening adapted to aline with either said type holder or one of said channels, and means for moving said type holder 5 relative to said member.

36. The combination of a type holding drum having a plurality of channels, a type holder, a slide movable radially of the drum and adapted to aline with either the type holder or a channel of the drum, said type holder being normally out of alinement with the drum, and means for moving the type holder for bringing it into alinement with one of the channels of the drum.

37. The combination of a storage member and a type holder, an interposed transferring member, and means for causing said holder and said transferring member to move in unison.

38. The combination of two type holders normally out of alinement, means moving transversely of both and adapted to transfer type from one to the other, and means for causing one of said holders and such transferring means to move in unison.

39. The combination of a magazine having a plurality of type holding channels, a member adapted to carry a row of type, said channels and member being adapted to be 30 out of alinement, mechanism moving transversely of both the member and channels and adapted to receive the type from one and deliver it to the other, and means for causing said member to come into alinement 35 with one of said channels.

40. The combination of a magazine having a plurality of type holding channels, a member adapted to carry a row of type, said channels and member being adapted to be 40 out of alinement, a slide moving transversely of both the member and channels and adapted to receive the type from one and deliver it to the other, means for caus-

ing said member to come into alinement with one of said channels, and manual 45 means for moving said slide.

41. The combination of two typeholders, one higher than the other, and mechanism operating to release to the action of gravity a line of type in the upper holder and 50 allow it to pass into the lower holder, and for transferring type one at a time from the upper holder to the lower.

42. The combination of two typeholders, one higher than the other, and mechanism 55 operating to release to the action of gravity a whole line of type in the upper holder and allow it to pass into the lower holder, and for transferring type one at a time from the upper holder to the lower, said mechanism having means adapted to engage the foremost type to limit the transfer.

43. The combination of two typeholders, one higher than the other, and mechanism operating to release to the action of gravity 65 a line of type in the upper holder and allow it to pass continuously to the lower holder, said mechanism having means adapted to engage each type to cause a successive transfer.

44. The combination of a channeled type case, mechanism adapted to stop the exit therefrom, a spring for holding said mechanism in stopping position, a tubular typeholder, and means for holding it in alinement with a channel of the type case when the stopping mechanism is in idle position and holding it out of such alinement when the stopping mechanism is in active position.

In testimony whereof, I hereunto affix my 80 signature in the presence of two witnesses.
